UNITED STATES PATENT OFFICE.

WILLIAM J. BROWN, OF MACON, GEORGIA.

VALVE.

1,306,576.

Specification of Letters Patent. Patented June 10, 1919.

Application filed July 7, 1917. Serial No. 179,197.

To all whom it may concern:

Be it known that I, WILLIAM J. BROWN, a citizen of the United States, residing at Macon, in the county of Bibb and State of 5 Georgia, have invented certain new and useful Improvements in Valves, of which the following is a specification.

This invention relates in general to valves, and particularly to an improved construction of what is known in the trade as a stop and waste.

As heretofore practised, a stop and waste which is employed to cut off the water from the service pipe, and, at the same time, drain 15 the plumbing fixtures, is never provided with means to prevent water from backing up through the waste opening, should for any reason the end of the waste opening become submerged. The present invention has 20 for its object to overcome this condition and to so construct the device that it will be impossible for the water to reenter the plumbing fixtures.

A further object is to incorporate the invention in a conventional type of stop and waste in a simple and cheap manner.

With these and minor objects, the invention will be more readily understood upon reference to the accompanying drawings, in 30 which:—

Figure 1 is an end view of a stop and waste with the invention applied thereto;

Fig. 2 is a side view of a stop and waste with the invention applied thereto; and 35 Fig. 3 is an enlarged detail view in section of the waste outlet illustrating the detail construction of the check valve.

Referring to the drawings in detail, 1 represents the combined stop and waste which 40 is constructed in the usual manner with a service inlet 2, a plug 3 having the usual service opening therethrough and a waste opening 4 which communicates, when the valve stem is turned in "off" position, with 45 the service opening which in turn communicates with the outlet 5 in the side of the casing of the stop and waste. 6 represents the inlet connection to the plumbing fixtures.

It is to be understood that no novelty resides in the construction of the stop and waste *per se*; it operates in a conventional manner, such as follows: When it is "on", the waste opening in the stem will be cut off, through means of the side of the casing, but when "off", the service opening in the stem 50 will be closed, so far as the inlet 2 is concerned, and the opening 4 in the stem will be in register position with the inlet connection 6 (see Fig. 1), which will permit the plumbing fixtures to be drained through 55 this opening and the outlet 5. In most instances it is desirable to extend the waste outlet beyond the side of the casing through means of a small tube, such as 7. Should 60 for any reason the end of this tube 7 become submerged, water would be very likely to back up through the tube and the waste outlet 5 into the plumbing fixtures. To prevent this, it is proposed by the present invention to employ a check valve 8 which 65 will permit the waste water to be readily discharged, but prevent the same from entering the plumbing fixtures. This check valve embodies a seat 9 for a ball 10, the seat 70 9 being provided with a threaded outer portion over which is threaded a retaining cap 11 having an opening 12. A strip of gauze or the like 13 is employed to prevent sediment from entering the valve seat through 75 the opening 12 and defeat the purpose of the ball, that is to say, prevent the sediment from getting between the valve and its seat 80 which would prevent the ball from properly seating.

I claim:—

An attachment for drain valves, comprising a waste outlet having a discharge terminating in an upwardly presented end above the valve casing, and a check valve in said upwardly presented end adapted to 90 permit the drainage from said valve through said outlet but close said outlet to back-flow from an outside source.

The foregoing specification signed at Ma- 95 con, Georgia, this 28 day of June 1917.

WILLIAM J. BROWN.
